UNITED STATES PATENT OFFICE.

GEORGE PSAREAS AND NICK BALEZOS, OF HOLYOKE, MASSACHUSETTS.

STEAM-ENGINE.

1,016,955.

Specification of Letters Patent. Patented Feb. 13, 1912.

Application filed May 12, 1911. Serial No. 626,765.

To all whom it may concern:

Be it known that we, GEORGE PSAREAS and NICK BALEZOS, Greek subjects, and residents of Holyoke, in the county of Hampden and 5 State of Massachusetts, have invented certain new and useful Improvements in Steam-Engines, of which the following is a full, clear, and exact description.

The object of this invention is to provide a 10 duplex reciprocating steam engine which is especially suitable for use as a pumping engine, which is of extremely simple construction and efficiency of operation, and in which the valves, and the controlling means therefor, are located in the steam chest, and in 15 which each valve controls both the steam inlet and exhaust ports of each cylinder, such valves being governed by the action of the pistons in their reciprocatory movements.

20 By reason of the organization of the valve mechanism comprised in this engine, including the controlling devices therefor, the two valves are constrained to have their movements each in a particular manner and time 25 with reference to the other, so that, for example, a piston upon coming to the right hand end of its cylinder will establish conditions for the forcing of the other piston then in the same end of the other cylinder to 30 the left hand end, whereupon such piston arriving at the left hand end will establish conditions for bringing the first named piston also to such left hand end, whereupon both pistons are again moved in close succession to the right hand end, and so on, repetitively in such order during the running of 35 the engine.

Under our improved valve constructions 40 and means for the control thereof, the strokes of the two pump pistons carried by the piston rods of the steam cylinder will be successively moved forwardly in the same direction, then successively moved backward in the same direction, so that a given stroke 45 of one piston is followed as a supplement of its stroke, by the other piston moving in the same direction, whereupon the pumping impulses of the second piston is practically a continuation of the first one, so that a maximum 50 of pumping pressure is exerted. And by having the steam cylinder valves and their controlling mechanism at locations enclosed by, and adjacent, the steam chest, so that no portion of the valve mechanism requires 55 space for occupancy at or alongside portions of the piston rods between the steam

cylinders and the pump cylinders, these cylinders, usually united by an integrally cast web or yoke, may be arranged in much closer endwise relations than heretofore, so that the 60 length of space necessary to be occupied by the pumping engine as a whole may be considerably less than heretofore usual.

The steam engine improvements are described in connection with the accompanying 65 drawings which show the engine in conjunction with a pump, and are set forth in the claims.

In the drawings:—Figure 1 is a side elevation of the engine and a pump designed to 70 be used in conjunction therewith. Fig. 2 is a sectional view of the pump taken on the line 2—2 Fig. 1, showing the arrangement of the valves therein. Fig. 3 is a plan view of the pump as seen below the line 3—3, Fig. 1, 75 showing one of the valve plates. Fig. 4 is a plan view as seen below line 4—4, Fig. 1, showing the steam chest of the engine and the arrangement of the valves and valve operating frames therein. Fig. 5 is a vertical 80 longitudinal sectional view through the engine, taken along the axis of one of the cylinders thereof. Fig. 6 is a cross sectional view of the engine taken on line 6—6, Fig. 1.

In the drawings:—7—7' represent the cylinders of the duplex pumping steam engine, in which reciprocate the pistons 8—8'. Above the upper walls of the cylinders is the steam chest 9, which is connected with the cylinders by means of the channels 10—10, 90 each of which has the ports 12 and 12' into said steam chest, through which the steam enters the cylinder and through which it is latterly exhausted. The two ports 12, 12' 95 for each channel are to all intents and purposes the same as a single wide port, but the small partitioning portion between them affords increased base having surface for the slide valve, next referred to. In the steam chest are two slide valves 13 and 13' each 100 having a chamber 14 in the bottom thereof, and having a groove in the top which engages for a sliding movement with the guide rod 15, the pair of which extend longitudinally in the steam chest and have thereon 105 the stops 16, which serve to limit the movements of the valves 13—13'. The valve 13 is connected, through the lever 17, to the blocks 19—19' which are rigidly connected by the frame 20, said lever 17 being by pivot 18, at 110 its center, connected to the bottom wall of the steam chest as shown in Figs. 4 and 6.

The frame 20 and the valve 13 have the lugs projecting therefrom having longitudinal slots therein in which the extremities of the lever 17 engage to allow for a sliding movement of the lever therein as the piston 8 imparts motion to said valve 13 through the frame 20 and the lever 17. The valve 13' is positively connected to the blocks 22-22' by the rigid frame 23.

- 10 Each block 19-19'-22-22' has a pin 24 secured thereto and protruding downwardly therefrom into its respective cylinder through an aperture 11 therefor in the bottom wall of the steam chest, at the opposite 15 ends of the cylinder, said blocks serving to close the mouths of the apertures and preventing any uncalled for entrance of steam from the cylinder into the steam chest, and vice versa.
- 20 An exhaust pipe 25^a is provided which is connected through the medium of the chambers 14 in the valves 13 and 13' with the exhaust ports 12' from the cylinders, by way of the exhaust passage 25 with which 25 such pipe 25^a has communication.

The steam enters the steam chest through the inlet pipe 26, and the one port 12 being open, as in Figs. 4 and 5, the steam passes therethrough to the cylinder 7, forcing the piston 8 forward until it strikes the pin 24 at the left which is moved forward, and by means of the block 22, and the frame 23 connecting it with the valve 13', said valve 13' is moved forward and the steam inlet port is uncovered allowing the steam to enter the cylinder 7' therethrough and to force the piston 8' forward to engage the pin secured to the block 19, when the operation is the reverse of the one described. When each valve is at 40 the extreme of its sliding movement, the chamber 14 in the bottom thereof covers the exhaust port from the cylinder and also the port or end of the passage 25 in communication with the exhaust pipe 25^a so the 45 steam is allowed to escape from the cylinder through the exhaust port therefrom, through the chamber 14, and through the exhaust passage 25 to the exhaust pipe 25^a.

The piston 8 in cylinder 7 operates the 50 valve 13' controlling the ports entering the cylinder 7'; and the piston 8' in the cylinder 7' operates the valve 13 which controls the ports entering the cylinder 7. For example, it will be assumed that the parts are in the 55 relative positions shown in Figs. 4 and 5, in which the right hand port 12 in the steam chest over the cylinders 7 is uncovered for steam entrance, while the left hand port 12 leading to the other steam cylinder 7' is 60 open for exhaust, the piston in the cylinder 7' being understood as having finished its rightward stroke and at the right hand end of its cylinder; the steam in the right hand end of the cylinder 7 will finally force the 65 piston 8 to the extreme leftward in such

cylinder 7, whereupon by abutment against the depending stud or pin 24, at such end it will slide the frame united blocks 22, 22' correspondingly to the leftward and through the connections 23 with the slide valve 13' 70 appurtenant to the other cylinder, such valve will be moved to the left, whereupon the right hand port appurtenant to cylinder 7' will be opened so that while the piston 8 remains in its extreme leftward position the 75 piston 8' in the other cylinder will move down to its extreme leftward position; but such piston 8' in coming to the leftward position will move the blocks 19, 19' and connecting frame 20, and through the lever 17 80 will move the slide valve 13 to the rightward so that the piston 8 will correspondingly move rightward, whereupon on the reaching of its limit of movement in that direction by striking against the depending 85 pin 24, the slide valve appurtenant to the piston 8' is shifted or reversed so that that piston 8' is moved down to the same end of the engine as occupied, in the other cylinder, by the piston 8. And it is, therefore, to be 90 clearly understood that the piston moving to the leftward is followed in the same leftward direction by the second piston which on its arrival at the left hand end establishes conditions causing the first piston to 95 be driven to the rightward so that upon its arrival at the end of its rightward stroke, the rightward stroke of the second piston will commence. Thus the stroke of the relatively second piston is in continuation of 100 that of the first one so that the pump pistons are correspondingly operated by very long, strong, high pressure pumping impulses.

In conjunction with the steam engine herein described and illustrated (the use of 105 which is most extensively in connection with a pump), the steam pump is shown as comprising the pumping cylinders 27-27' in which reciprocate the pistons 28-28' actuated by the piston rods 29-29' to the other extremity of which are secured the steam pistons 8-8' respectively. The water enters the pump through the inlet pipe 30 and passes alternately through the valves 31-31' on the backward stroke of the pistons 28-28' and the forward stroke of the pistons cause the closing of the valves 31-31' and the water is forced through the valves 32-32' and out of the pump through the outlet pipe 33.

We claim:

1. In a duplex pumping steam engine, in combination, a pair of cylinders arranged side by side, and a steam chest thereover, having oppositely located sets of inlet and exhaust ports leading from the steam chest to the respective cylinders, and having opposite pairs of apertures communicating between the end portions of the cylinders and the valve chest, a pair of slide valves 125 130

for alternately opening and closing the ports of the respective cylinders, frames 5 slideable in the steam chest and having members projecting through said apertures into the opposite ends of the cylinders to be alternately engaged by the pistons, one of the frames over one cylinder, having operative connection with the slide valve controlling the ports of the other cylinder, and means 10 between the other of said frames and the relatively opposite slide valve for causing from the movements of such frame, the sliding movement of the latter named valve.

2. In a duplex pumping steam engine, 15 in combination, a pair of cylinders arranged side by side, and a steam chest thereover, having oppositely located sets of inlet and exhaust ports leading from the steam chest to the respective cylinders, and having opposite pairs of apertures communicating between the end portions of the cylinders and the valve chest, a pair of slide valves 20 for alternately opening and closing the ports of the respective cylinders, frames 25 slideable in the steam chest and having members projecting through said apertures into the opposite ends of the cylinders to be alternately engaged by the pistons, one of the frames over one cylinder having trans- 30 verse members connecting it with the slide valve controlling the ports of the other cylinder, and an intermediately pivoted lever engaging the other frame and the slide valve relatively opposite thereto.

3. In a duplex pumping steam engine, in combination, the cylinders, having steam inlet and exhaust ports opening therewith, and pistons therein, slide valves for alternately

opening and closing the inlet ports and having chambers in the base thereof for alternately opening and closing the exhaust ports, and also having grooves in their top, 40 guide rods above the valves with which the grooved tops of the valves engage, stops on said rods for limiting the movements of the 45 valves, pin protruding downwardly from the steam chest into the cylinders, slideable blocks by which said pins are carried, means for uniting a pair of blocks, and means operated by the united pair of blocks 50 for operating the slide valves, respectively opposite thereto.

4. In a reciprocating steam engine, in combination, a steam chest, a cylinder, and a wall separating them, having exhaust and 55 inlet ports, and also having apertures leading through the said wall from the steam chest to opposite ends of the cylinders, a slide valve for alternately opening and closing the inlet and exhaust ports, a piston in 60 the cylinder and a frame slideable in the steam chest, comprising blocks having closing relations to said apertures and provided with pins extending through said apertures into the opposite ends of the cylinders to be alternately engaged and moved by the piston, 65 said frames operatively co-acting with the slide valve.
